(57) **CLAIM**

The ornamental design for a sensor, as shown and described.

DESCRIPTION

FIG. 1 is a bottom isometric view of the sensor. FIG. 2 is a top isometric view of the sensor of FIG. 1. FIG. 3 is a front elevation view of the sensor of FIG. 1. FIG. 4 is a right side elevation view of the sensor of FIG. 1. FIG. 5 is a rear elevation view of the sensor of FIG. 1. FIG. 6 is left side elevation view of the sensor of FIG. 1. FIG. 7 is a top plan view of the sensor of FIG. 1; and, FIG. 8 is a bottom plan view of the sensor of FIG. 1. The evenly dotted broken lines in the drawings illustrate unclaimed features of the sensor and form no part of the claimed design. The dash-dot-dot-dash broken lines in the drawings represent borders of unclaimed portions of the design and form no part of the claimed design.
